DESIGN FOR A UTENSIL SCRAPER OR SIMILAR ARTICLE

Norma G. A. Steinberg, Oak Park, Ill.

Application July 3, 1936, Serial No. 63,636

Term of patent 7 years

To all whom it may concern:

Be it known that I, Norma G. A. Steinberg, a citizen of the United States and residing in the village of Oak Park, in the county of Cook and State of Illinois, have invented a new, original, and ornamental Design for a Utensil Scraper or Similar Article, of which the following is the specification, reference being had to the accompanying drawing, forming a part thereof.

On the drawing:

Fig. 1 is a side elevational view of a utensil scraper showing my new design.

Fig. 2 is a cross sectional view thereof taken on line 2—2 of Fig. 1.

Fig. 3 is a side elevation of the under side of the utensil scraper, said side being that opposite the one shown in Fig. 1.

I claim:

The ornamental design for a utensil scraper or similar article, as shown.

NORMA G. A. STEINBERG.
